Primary Examiner — Keith J Wilson(74) *Attorney, Agent, or Firm* — Warner Norcross + Judd LLP**(57) CLAIM**

The ornamental design for a dual media nozzle, as shown and described.

DESCRIPTION

FIG. 1 is a front perspective view of the dual media nozzle; and,

FIG. 2 is a side view thereof.

Features shown in broken lines do not form any part of the claimed design. Any broken lines immediately adjacent the solid-line portions of the design form the boundary of the design. The remaining broken lines represent the dual media nozzle, and form no part of the claimed design.
